UNITED STATES PATENT OFFICE.

THOMAS SHIPLEY, OF YORK, PENNSYLVANIA.

AMMONIA-COMPRESSOR.

1,081,159.

Specification of Letters Patent.

Patented Dec. 9, 1913.

Application filed March 19, 1913. Serial No. 755,493.

To all whom it may concern:

Be it known that I, THOMAS SHIPLEY, of the city of York, in the county of York and the State of Pennsylvania, have invented a new and useful Improvement in Ammonia-Compressors, of which the following is a specification.

My invention relates to ammonia or other fluid compressors used in connection with machinery for refrigerating and ice making purposes, and it has to do with means for holding the stuffing box of the compressor cylinder central with the bore of the cylinder and in axial alinement therewith, and preventing it from being thrown out of such alinement by the setting up of the bolts by which the cylinder head, of which it forms part, is secured to the cylinder.

The improvement is illustrated in the accompanying drawings in which—

Figure 1 is a side elevation of so much of a compressor as is needed to illustrate the improvement, that position of the same which embodies my invention being shown in section. Fig. 2 is a transverse vertical section on line 2—2, Fig. 1, on somewhat enlarged scale.

The particular machine shown in the drawing is a double acting compressor of well known type, to the general features of which I lay no claim, and which it is unnecessary to describe further than to say that A is the cast frame in which the working parts are mounted; B is the compressor cylinder; C is the piston-rod carrying the piston, and connected at the other end to a cross head D mounted to slide in the cross head barrel A' forming part of the casting A, and driven in the customary way from engine shaft E through the intermediary of a crank connection.

B' is the compressor cylinder head provided with stuffing box F through which the piston rod C passes, said head being secured in place by the usual bolts b.

I come now to the parts in which my improvement is embodied.

G is a brace and guide, the annular central portion of which fits snugly upon the cylindrical neck of the stuffing box F as shown more clearly in Fig. 2, the ends of this brace at top and bottom fitting against seats H formed for them in the casting A, and being held tightly thereto by bolts i. The axis of the bore of the annular central portion of the brace G is on the prolongation

of the axis of the compressor cylinder. The brace fits the neck of the stuffing box snugly, but not too tightly to prevent a sliding movement of the one relatively to the other. Thus in setting up the bolts which secure the cylinder head A' in place, the brace G furnishes a center bearing in which the stuffing box may slide, while maintained in axial alinement with the bore of the cylinder B. Under this construction there is no possibility of the stuffing box being pulled out of alinement by the setting up of the bolts. In order to assure the rigidity and permanence of the structure in this regard, I connect the cross-head barrel A' with that portion A² of the casting A which holds the cylinder B, by an overhead bridge piece A³, cast in one with these parts and form the top seat H for the brace on this bridge. Heretofore it has been usual to connect the top by longitudinal stay bars or bolts. Connections of this kind, however, are objectionable not only because they do not furnish a convenient and safe seat for the upper end of brace G, but because they are liable to vary in length from expansion and contraction, and other causes, and these variations tend to throw the parts of the machine out of line. By substituting for these bolts a solid continuous bridge piece cast in one with the parts A', A², all trouble from this source is avoided and a permanent and secure seat for the brace is provided at the top.

Having described my improvement and the best way now known to me of carrying the same into practical effect, what I claim as my invention and desire to secure by Letters Patent, is as follows:

1. The combination of the compressor cylinder and frame in which it is mounted: the center brace and guide G mounted and secured in said frame and having an annular portion in axial alinement with the barrel of the cylinder; the cylinder head, bolted to the cylinder; and the stuffing box F on the cylinder head fitting and taking a sliding bearing in said center brace, whereby during the operation of setting up the bolts by which the cylinder head is fastened in place, the stuffing box will be maintained and held in accurate axial alinement with the cylinder barrel, as hereinbefore shown and described.

2. The combination with the compressor cylinder and frame in which the same is mounted, of the bridge A³ connecting, and

- cast in one with, the portions A' and A² of the frame in which the cross head and the cylinder respectively are mounted, the center brace and guide G secured at its ends to seats 5 H formed on the bridge A³ above and on the body of frame A below respectively, and having an annular intermediate portion in axial alinement with the cylinder barrel, the cylinder head bolted to the cylinder, and the 10 stuffing box thereon fitting and taking a sliding bearing in said center brace, whereby during the operation of setting up the bolts

by which the cylinder head is fastened in place, the stuffing box will be maintained and held in accurate alinement with the cylinder barrel, as hereinbefore shown and described. 15

In testimony whereof I affix my signature in presence of two witnesses.

THOMAS SHIPLEY.
